UNITED STATES PATENT OFFICE

144,610

DESIGN FOR A CAR SEAT END SUPPORT

James V. Conway, Hinsdale, Ill., assignor to Heywood-Wakefield Company, Gardner, Mass., a corporation of Massachusetts

Application February 6, 1946, Serial No. 126,306

Term of patent 7 years

(Cl. D15—8)

To all whom it may concern:

Be it known that I, James V. Conway, a citizen of the United States, residing at Hinsdale, in the county of DuPage and State of Illinois, have invented a new, original, and ornamental Design for Car Seat End Support, of which the following is a specification, references being had to the accompanying drawing, forming a part thereof.

Figure 1 is a side perspective view of a car seat end support showing my new design, the opposite side thereof being plain;

Figure 2 is a rear end elevational view of the same.

This application is a continuation-in-part of my copending application Serial No. D-120,944, filed July 25 1945, for car seat.

I claim:

The ornamental design for a car seat end support, as shown and described.

JAMES V. CONWAY.
